UNITED STATES PATENT OFFICE.

ISAAC H. MILLIKEN, OF ASPINWALL, PENNSYLVANIA, ASSIGNOR TO THE McCONWAY & TORLEY COMPANY, OF PITTSBURGH, PENNSYLVANIA, A CORPORATION OF PENNSYLVANIA.

DRAFT-RIGGING.

1,284,415.

Specification of Letters Patent. Patented Nov. 12, 1918.

Application filed August 8, 1917. Serial No. 135,043.

To all whom it may concern:

Be it known that I, ISAAC H. MILLIKEN, a citizen of the United States, residing at Aspinwall, in the county of Allegheny and State of Pennsylvania, have invented certain new and useful Improvements in Draft-Rigging; and I do hereby declare the following to be a full, clear, and exact description of the invention, such as will enable others skilled in the art to which it appertains to make and use the same.

My invention relates to the construction of draft rigging for railway cars, and particularly to means for operatively connecting the stem of the car coupler to the draft yoke. The object of the invention is to provide simple, strong and durable means constituting an efficient and reliable mode of attaching the coupler to the draft yoke so as to permit easy assembly and disassembly of the connected parts. A further object of the invention is to provide a construction of the character noted which is especially well adapted for use where the coupler is designed to perform an extended lateral swinging movement when the car to which it is attached is passing around a curve. These objects are accomplished, generally stated, by providing the coupler with a shouldered rear end, and by fashioning the draft yoke with a hooded forward end into which the rear end of the coupler may be inserted, these parts being connected by a pair of transversely extending key members which engage the rear faces of the lateral walls of the hooded portion of the yoke and also engage the corresponding shoulders at the rear end of the coupler, said shoulders of the coupler stem and the operating portions of the key members being correspondingly curved if it is desired to allow the coupler to have an extended swinging movement.

In the drawings illustrating the preferred embodiment of my invention, the scope whereof is pointed out in the claims,

Figure 1 is a plan view of a draft rigging embodying the invention, the forward portion of the coupler and the cushioning

units normally mounted within the yoke being omitted.

Fig. 2 is a side elevation of the construction illustrated in Fig. 1.

Fig. 3 is a detail sectional view, taken on the line 3—3, Fig. 2.

Fig. 4 is a transverse sectional view looking forwardly, taken on the line 4—4, Fig. 2.

In the drawings, 1 indicates a car coupler and 1^a is the draft yoke. Except for the features of construction set forth in the claims the coupler and draft yoke may be of any desired form.

The rear end of the coupler is shouldered, being provided at its upper and lower sides with lugs or bosses 2 whose forward faces are preferably undercut and curved concavely, as indicated at 3, to form pivot bearings that are respectively adapted to coöperate with key members 4 having correspondingly curved and beveled projections or bearings 5.

The forward ends of the arms 6 of the draft yoke 2 are widened, as at 7, and are connected by oppositely disposed walls 8, thus giving to the forward end of the draft yoke a hooded or box-like form. If the coupler is designed to swing laterally, the space between the walls 8, 8 of the yoke is made sufficient to permit the desired extent of lateral swinging. The rear faces of the walls 8 of the hooded portion of the draft yoke 2 are preferably inclined or beveled adjacent the respective arms 6 of the yoke. These inclined faces 9 are adapted to be engaged by correspondingly inclined faces 10 on the key members 4 when the mechanism is subjected to draft forces, the result being to offer resistance to any tendency of the arms 6 of the yoke to spread or separate at their forward ends.

The key members 4 interposed between the oppositely extending pivot lugs 2 of the coupler stem, and the rear faces of the oppositely disposed walls 8 of the hooded portion of the draft yoke are each preferably provided with a forwardly extending portion or tongue 11 that preferably fills the space between the walls 8, 8 of the yoke, the

key members 4 thus being substantially T-shaped. The tongues 11 of the keys 4 are of sufficient length to prevent the escape of the keys when the coupler 1 is in the extreme 5 buffing position.

The rear end 12 of the coupler is adapted to engage the forward follower (not shown) of the well known cushioning unit that is commonly mounted between the arms 10 6, 8 of the draft yoke. Ordinarily the yoke of a draft rigging moves rearwardly with the coupler in buffing, an open space thus being created between the rear follower of the cushioning unit and the rear end of the 15 draft yoke. When the buffing force ceases to act the parts return to normal position, closing up this space. In the preferred embodiment of my invention as heretofore described the open space or "slack" corresponding to the compression of the springs 20 of the cushioning unit would be distributed at several points, part occurring between the coupler 1 and the key members 4, a little occurring between the keys and the hooded 25 end of the draft yoke, and some being between the rear end 13 of the yoke and the rear follower, thus preventing the full strain coming at one time on the mechanism when the parts return to normal position after 30 a buffing operation. The vertical height of the rear end of the coupler is preferably substantially equal to the distance between the interior faces of the yoke arms 6, the rear end of the coupler being supported by 35 the yoke rather than by resting upon the lower key member 4.

In assembling the draft rigging the rear end of the coupler 1 is inserted longitudinally into the hooded end of the draft yoke 40 2 and is pushed rearwardly far enough to allow the keys 4 to be placed in front of the pivot lugs 2 of the coupler at the rear of the hooded end of the yoke. The coupler 1 is then drawn forwardly to normal position, thus causing the tongues 11 of the 45 T-shaped keys 4 to enter the space between the lateral walls 8 of the hooded end of the draft yoke and bringing the inclined shoulders 10 of the keys into engagement with 50 the corresponding inclined portions of the rear faces of the walls 8 of the yoke. The spring unit (which may be the well known arrangement of springs and followers) is then forced into position between the arms 6 55 of the yoke to the rear of the coupler and the assembled mechanism may then be applied to the underframing of a car in the usual manner.

I claim:

60 1. In a draft rigging, the combination with a coupler having a shouldered rear end, of a draft yoke having a hooded forward end, and means for operatively connecting

said coupler and yoke, said means involving a pair of transversely extending and longitudinally movable key members engaging the rear faces of oppositely disposed walls of the said hooded portion of the draft yoke, the respective key members also engaging the corresponding shoulders at the rear end 65 70 of said coupler, and said coupler and yoke being relatively movable in buffing.

2. In a draft rigging, the combination with a coupler provided with oppositely disposed shoulders, of a yoke, and means 75 for operatively connecting said coupler and yoke, said means involving a pair of substantially T-shaped keys adapted to be dissociated from said draft yoke by being moved longitudinally with respect to said 80 yoke.

3. In a draft rigging, the combination with a coupler having oppositely disposed pivot lugs, of a draft yoke, and a plurality of key members forming bearings for the 85 said pivot lugs and adapted to transmit draft forces from said coupler to said yoke.

4. In a draft rigging, the combination with a coupler provided with oppositely disposed shoulders on its rear end, of a 90 draft yoke, and a plurality of key members operatively connecting said coupler and yoke, said yoke being provided with a plurality of spaced members, and each of said key members being adapted to engage a 95 plurality of said spaced members to limit the forward movement of said keys with respect to said yoke.

5. In a draft rigging, the combination with a coupler, of a draft yoke having a 100 hooded forward end, and a plurality of substantially T-shaped keys for operatively connecting said coupler and yoke to transmit draft forces from the coupler to said yoke.

6. In a draft rigging, the combination with a coupler having a shouldered rear end, of a draft yoke having its upper and lower arms widened adjacent their forward ends, means for connecting the widened portions of said arms to form a hood at the forward end of said yoke, and means longitudinally movable with respect to said yoke for rotatably connecting said coupler and draft yoke, said coupler being insertible longitudinally into the hooded portion of said yoke, the vertical height of the rear end of the coupler being substantially equal to the distance between the interior faces of said yoke arms, and at least one of said shoulders on the coupler being adapted to engage the adjacent face of one of the arms of said 110 115 120 yoke.

7. In a draft rigging, the combination with a coupler having oppositely disposed undercut shoulders at its rear end, of a 125

draft yoke having inclined faces, and key members respectively interposed between said undercut shoulders of the coupler and said inclined faces of the draft yoke, said 5 keys being provided with inclined faces corresponding to the portions of the yoke and coupler with which they engage.

8. In a draft rigging, the combination with a coupler having a shouldered rear end, 10 of a draft yoke having its upper and lower arms connected to form a hood at the forward end of said yoke, said coupler and yoke

being relatively movable longitudinally in buffing, and a plurality of keys engaging the corresponding shoulders at the rear end of 15 the coupler to operatively connect said coupler and draft yoke, said coupler being insertible longitudinally into the hooded portion of said yoke, and the vertical height of the rear end of the coupler being substantially equal to the distance between the 20 interior faces of said yoke arms.

In testimony whereof I affix my signature.
ISAAC H. MILLIKEN.
